Stephen Threlkeld
James Polent

6584X

The schedule referred to us, shows James Polent and making part of the same
containing a description in the name of the said Stephen Threlkeld himself of
his improvement in the manufacture of hats by hardening the body on the
cone.

In all his往來 these presents shall suffice. Be it known that Stephen
Threlkeld of Glastonbury in the County of Hartford and State of Connecticut
invent has invented a new and useful improvement in the manufacture
of hats by hardening the body on a cone and that the following is a
full and exact description of the construction and operation of the said
machine as invented or improved by me. My claim is for admitting
steam into the cone on which hat bodies are formed after covering the
cone with a copper shell. The cone (No. 2) on which the hat body is
formed is provided with holes, when the web which constitutes the body
is lowered upon the cone it is covered with a cloth and over the whole is put
the cap (No. 3). It is then taken to the boiler (No. 1) and placed directly on
the steam pipe (No. 4) and the cap (No. 3) is set in motion by the steam
by this process will harden the hat body.
